SOOT BLOWER

Harry E. Brelsford, Birmingham, and Curtis L. Howse and Frank Bowers, Detroit, Mich., assignors to Diamond Power Specialty Corporation, Detroit, Mich., a corporation of Michigan

Original application September 10, 1932, Serial No. 632,614. Divided and this application September 10, 1934, Serial No. 743,398. Renewed December 30, 1937

1 Claim. (Cl. 122—392)

This invention is directed to means for cleaning boilers or other heat exchange apparatus and contemplates the provision of means for discharging adjacent the heating surfaces thereof, 5 jets of cleaning fluid to dislodge from said surfaces deposits which may be formed thereon.

This application is a division of our co-pending application, Serial Number 632,614, filed September 10, 1932.

10 The numerous objects and advantages of the invention will become apparent as the following description proceeds particularly when reference is had to the accompanying drawing wherein like reference characters designate corresponding parts throughout all views and wherein

Fig. 1 is a plan view of one form in which our invention may be embodied;

Fig. 2 is a sectional view taken substantially on the line 2—2 of Fig. 1;

20 Fig. 3 is a sectional view taken substantially on the line 3—3 of Fig. 1;

Fig. 4 is a section through the pilot valve controlling the pistons actuating the element and valve;

25 Fig. 5 is a detail view of the piston ring used in the piston shown in Fig. 2.

Referring now to Figures 1 to 5 inclusive, when air is admitted by a suitable controller adapted to supply air in puffs through line 102 on top of 30 the piston 132, this is depressed carrying with it the pawl 133 which acts against the spring 144 to rotate the gear 145. Gear 145 is fixed to a suitable blower element 97 adapted to discharge cleaning fluid adjacent portions of the fluid heater or the like to be cleaned.

35 In the line 102 leading from the controller is provided a T 146 from which leads line 147 to the pilot valve 148. At the same time that air is admitted on top of piston 132 it enters the pilot valve 148 through line 147, acting on the face of piston 149. This is connected through rod 150 to valve 151 so that when the piston 149 is moved to the right in Figure 4 it moves the valve 151 from its seat against the action of the spring 153.

40 The control valve 158 normally rests against its seat 159. The valve 158 is attached through rod 134 to piston 160 mounted in piston housing 168. Cleaning fluid from the supply line 81 entering the operating head through opening 135 acts both on the top of the valve 158 and on the 45 face of the piston 160. Piston ring 135 is provided in piston 160, the piston ring being provided with a graduated opening 135' (shown in 50 Figure 5) admitting the cleaning fluid to the

space 137 in the piston housing 168. Thus, under normal conditions the same pressure is established on each side of the piston 160, the valve being kept closed by the action of spring 169.

Upon venting of the pressure in the space 137 5 above the piston it is obvious that the pressure of the cleaning fluid acting on the face 138 of piston 160 will move the piston against spring 169, to open the valve.

10 It is the function of the pilot valve 148 hereinbefore described to provide a vent for the pressure in the space 137 permitting the valve to open.

As hereinbefore described, when the fluid pressure is admitted to the pilot valve 148, it moves the valve 151 from its seat 152 so that the pressure from the space 137 in the piston housing 168 passes through line 154, through valve 151 on top of the valve 171.

15 Referring now to Figure 3, it will be noted that the lever 155 is pivotally supported on the lug 156, this lever being adapted to engage the cam 157 fixedly mounted on gear 145. Cam 157 is made of the desired length in order to fix the period of opening of the supply valve 158. Thus, the length of the cam determines the fraction of 20 rotative movement of the element 97 over which the control valve 158 is open.

25 When the lever 155 is engaged by the cam 157 it raises the stem 170 upwardly, moving the valve 171 away from its seat 172. When the valve 171 30 is moved from its seat 172, fluid pressure, admitted to the pilot valve 148 from the space 137 in the piston housing 168, passes to exhaust through openings 139.

35 It will thus be seen that when the controller admits the cleaning fluid to line 102 through T 146 and line 147 to pilot valve 148, that the result is to vent the pressure from space 137 only when the lever 155 has engaged the cam 157 so that both of the valves in the pilot valve are open. 40

If this trigger 155 does not engage the cam 157 the pilot valve 148 will not be fully open to exhaust and, consequently, the supply valve 158 will not open.

45 It will be noted from Figure 2 that the amount of movement of the piston 160 is determined by the abutting of the skirt of the piston against the shoulder 167. This movement is sufficient to withdraw the valve 158 entirely within the piston housing 168, thus providing a relatively unobstructed passage for the cleaning fluid from line 81 to element 97, affording a construction giving the minimum pressure drop through the operating head.

50 Thus, in the operating head, as shown in Fig- 55

ure 3, the gear 145 may be provided with eighty teeth. The pawl 133 may be adapted to actuate gear 145 the distance of four teeth at each power impulse, thus requiring a total of 20 impulses 5 to rotate the nozzled tube 97 through exactly 360°. To accomplish this result with the second type of controller described, the extent of the arcuate port 234 may be made with such relation to gear 245 as to insure that the gear 245 is 10 moved a distance of twenty teeth by the pawl 243 while the arcuate port 234 in the rotatable valve member 233 is in registry with one of the holes 235 in the stationary valve plate 236. It has been found in practice that such a proportioning of the parts affords a very satisfactory 15 operation but it should be pointed out that these proportions may be varied to secure any desired actuation of the boiler cleaner operating head. With the construction of the second controller 20 it is convenient to limit this amount of arcuate actuation to one complete revolution or less, whereas in the controller of the first type described, arcuate travel may very conveniently be three complete rotations or any fraction thereof. 25 It is obvious that the proportions of the parts might be varied in both instances to secure any desired results.

While one form of the invention has been described in some detail, it is to be clearly understood that the description is for the purposes of 30 illustration only and is not definitive of the limits of the inventive idea. The right is reserved to make such changes in the details of construction and arrangement of parts as will 35 fall within the purview of the attached claim.

What we claim as our invention is:
In a fluid heater cleaner, a rotatable blower

element, a source of cleaning fluid under pressure, a cleaning fluid supply pipe connecting the source of cleaning fluid to the blower element, a valve in said supply pipe controlling the flow of cleaning fluid from said source to said blower element, a piston connected to said valve for actuating the same, a cylinder in which said piston is mounted, said cylinder being so associated with said supply pipe that one side of the piston in the cylinder is exposed to the pressure of the 5 cleaning fluid in the supply pipe, means including a second piston adjacent said blower element for moving the same, a cylinder in which said second piston is mounted, means for intermittently supplying cleaning fluid from said source to said 10 last mentioned cylinder to effect a reciprocation of the piston therein and a step by step movement of said blower element, a plunger exposed to the pressure of the cleaning fluid acting on said second mentioned piston, said plunger thus 15 being adapted to reciprocate in unison with said second mentioned piston, a valve connected to said plunger for controlling the exhaust of pressure on one side of said first mentioned piston whereby the cleaning fluid acting on the other 20 side of said first mentioned piston may move the same to open said valve, and a second valve so controlled by the rotation of said blower element for controlling the effective operation of said plunger actuated valve, that said main cleaning 25 fluid controlled valve is periodically opened and closed during a predetermined portion of the rotation of the blower element.
